UNITED STATES PATENT OFFICE.

EVERETT B. STACKPOLE, OF SEATTLE, WASHINGTON.

CUFF-CLASP.

1,243,775.

Specification of Letters Patent. Patented Oct. 23, 1917.

Application filed December 16, 1916. Serial No. 137,328.

To all whom it may concern:

Be it known that I, EVERETT B. STACKPOLE, a citizen of the United States, residing at Seattle, in the county of King and State of Washington, have invented certain new and useful Improvements in Cuff-Clasps, of which the following is a specification:

This invention relates to clasps for cuffs, and more particularly to the type which have yokes embracing the outer or meeting-edges of the cuff and locking-means extending through a button-hole in the cuff.

The object of the invention is to provide a clasp or clamp of this character which may be readily applied and removed with the least possible effort, one which will not become inadvertently unfastened, and one which is inexpensive to manufacture.

Briefly, the invention comprises a substantially V-shaped plate adapted to receive and embrace the meeting-edges of the cuff, having near the end of one of its arms a pivoted button or head to the inner side of which is secured a prong arranged to pass in and out through a button-hole of the cuff, and to engage at its inner end with the inside of the opposite edge of the cuff when the pivoted button is pressed inward and against the V-shaped plate. The interior of the other arm of the plate may be provided with short prongs to hold such arm in proper position with respect to the arm which carries the pivoted button; and a second button-hole in the cuff is not necessary. A spring coöperates with the movable prong to insure against inadvertent withdrawal of the prong. The pivoted head replaces the upper or outer member of the ordinary cuff-button, and may be ornamented as desired.

The invention will be better understood by reference to the accompanying drawing, wherein:

Figure 1 illustrates the clamp in its closed position on a cuff, as seen from the top edge;

Fig. 2 represents a side view of a portion of a cuff provided with a clasp constructed according to the present invention;

Fig. 3 is an enlarged side-elevation of the clasp in its closed position, as in Fig. 1, but detached from the cuff;

Fig. 4 is an enlarged side-elevation of the clasp in its open position;

Fig. 5 is a view similar to Fig. 4, except that part of the V-shaped plate is shown in section; and

Fig. 6 is a side view of the V-shaped base-plate with the pivoted head removed.

As illustrated, the clasp comprises a substantially V-shaped plate or band 1, into the angle of which are received the meeting-edges 2 of the folded cuff 3, as clearly shown in Figs. 1 and 2. The angle of this plate 65 may be varied as desired. One arm 4 of the plate has on its outer side a raised portion 5, having a transverse internal bore adapted to accommodate the pivot-pin 6 of a button or head 7 which lies normally flat 70 against the arm 4, but which may be swung outwardly to the position indicated in Figs. 4 and 5, through an angle of about 60°. The outer surface of the head 7 may be ornamented as indicated in Fig. 2, since it takes 75 the place of the outer member of the ordinary link cuff-button. Near its end, the arm 4 may be extended laterally, slightly, and is provided with an aperture 8, which aperture 80 is covered by the button 7 when the latter assumes its position in use flat against the arm 4. On the inner side of the button 7, and in position to be moved in and out through the aperture 8, is rigidly secured a 85 prong 9, slightly tapered, so as to have a point 10 at its inner end. When the button 7 is in the position shown in Fig. 3, in use, the point 10 lies sufficiently close to the inside of the other arm 11 of the V-shaped plate 1, to engage the fabric of the inside 90 of the cuff which lies beneath the arm 11. Secured also to the inside of the head 7, and adjacent to the prong 9, there is a leaf-spring 12 which normally diverges toward its outer end from the prong 9. It will be 95 apparent that the spring will prevent inadvertent withdrawal of the prong 9 through the aperture 8, that is, from the position shown in Fig. 3, but that it will yield upon outward pressure of the head or button 7 away from the arm 4 and assume a nesting position along the inside of the prong 9 during such movement, as indicated in Figs. 4 and 5. The prong 9 and the spring 12 are both slightly curved near their 100 inner ends to allow them to move through

105

the aperture 8 during swinging of the button 7 on the pivot 6. The inside of the arm 11, opposite the point 10 of prong 9, may be provided with notches or points 13 to assist 5 in the prevention of any slipping of the cuff, and one or more of such points or notches may be likewise provided on the inside of arm 4, as at 14, for the same purpose, although this will ordinarily not be 10 necessary as the prong 9 and the spring 12 which pass through a button-hole of the cuff will generally serve to prevent any relative movement of the cuff on that side of the clasp. The outer surface of the end 15 of arm 11 may be ornamented or plain, as desired.

The operation of the device in use will be apparent from the foregoing description. The cuff 3 is folded or rounded in the usual 20 manner and its meeting-edges inserted in the V-shaped opening of the plate 1, the button 7 having first been moved to its extreme outward position, as shown in Fig. 4. The point of prong 9 will then be opposite 25 the button-hole of the cuff, and firm pressure rearwardly and downwardly upon the head 7 will cause the prong 9 to penetrate the button-hole and assume the position of use shown in Fig. 1. The point 10 of the prong will thereupon firmly engage the inside of the portion of the cuff over the prongs 13, and the fabric will be slightly depressed in the notch between the prongs. No slipping of this portion of the cuff 30 around the point 10 can therefore occur. As the head 7 reaches its position flat against the arm 4, the spring 12 can assume its position of rest away from the prong 9, as in Fig. 1. Inadvertent outward 35 movement of the prong 9, and consequent release of the cuff, can therefore not occur. To remove the button the operation is reversed. Pressure upon the under, preferably concaved, side 15 of the button 7 in an 40 outward and forward direction will cause the button 7 to rotate through an angle of about 60° on its pivot 6, drawing the prong 9 and the spring 12 through the aperture 8 and the button-hole of the cuff, the spring 45 12 being by this movement compressed against the underside of the prong 9. The clasp is then in its open position, as shown in Fig. 4. Operation of the device can best be effected by manipulating the button 7 50 with the thumb and by guiding the arm 11 and therefore prongs 13 into position by means of the fingers.

The device is obviously simple to operate and is quite readily applied with one 60 hand while the other maintains the cuff in its rounded or partly folded position of wear.

I claim:

1. A cuff-clasp, comprising a substantially V-shaped plate adapted to embrace

the meeting-edges of the cuff and provided with an aperture in one of its arms, a member pivotally attached to said arm and having a prong movable through said aperture and a button-hole in the cuff, and means for maintaining the member in its inner position. 70

2. A cuff-clasp, comprising a substantially V-shaped plate adapted to embrace the meeting-edges of the cuff, a button pivoted 75 to one of the arms of said plate, and a prong attached to said button and movable through a button-hole in the cuff to engage the portion of said cuff beneath the other arm of said V-shaped plate. 80

3. A cuff-clasp, comprising a substantially V-shaped plate adapted to embrace the meeting-edges of the cuff, a button pivoted to one of the arms of said plate, a prong attached to said button and movable through 85 a button-hole in the cuff to engage the portion of said cuff beneath the other arm of said V-shaped plate, and means for maintaining the prong in such engagement. 85

4. A cuff-clasp, comprising a substantially V-shaped plate adapted to embrace the meeting-edges of the cuff, a button pivoted to one of the arms of said plate, a prong attached to said button and movable through 90 a button-hole in the cuff to engage the inside of the portion of said cuff beneath the other arm of said V-shaped plate, and a spring for maintaining the prong in such engagement. 95

5. A cuff-clasp, comprising a substantially V-shaped plate adapted to embrace the meeting-edges of the cuff and provided with an aperture in one of its arms, a button pivoted to said arm and covering said aperture in the cuff-fastening position, and 100 a prong attached to said button and movable through said aperture and a button-hole in the cuff to engage the inside of the portion of said cuff beneath the other arm of said V-shaped plate. 105

6. A cuff-clasp, comprising a substantially V-shaped plate adapted to embrace the meeting-edges of the cuff and provided with an aperture in one of its arms, a button pivoted to said arm and covering said aperture 110 in the cuff-fastening position, a prong attached to said button and movable through said aperture and a button-hole in the cuff to engage the inside of the portion of said cuff beneath the other arm of said V-shaped plate, and means for maintaining the prong in such engagement. 115

7. A cuff-clasp, comprising a substantially V-shaped plate adapted to embrace the meeting-edges of the cuff and provided with 120 an aperture in one of its arms, a button pivoted to said arm and covering said aperture in the cuff-fastening position, a prong attached to said button and movable through said aperture and a button-hole in the cuff 125 130

to engage the inside of the portion of said cuff beneath the other arm of said V-shaped plate, and a spring for maintaining the prong in such engagement.

- 5 8. A cuff-clasp, comprising a substantially V-shaped plate adapted to embrace the meeting-edges of the cuff, a button pivoted to one of the arms of said plate, a prong attached to said button and movable through 35 a button-hole in the cuff to engage the inside of the portion of said cuff beneath the other arm of said V-shaped plate, and a leaf-spring attached at one end to said button beside said prong but normally diverging 40
10 from the prong along its free end for maintaining said prong in engagement with the 45 cuff.

9. A cuff-clasp, comprising a substantially V-shaped plate adapted to embrace the 20 meeting-edges of the cuff, a button pivoted to one of the arms of said plate, a prong attached to said button and movable through a button-hole in the cuff to engage the inside of the portion of said cuff beneath the 25 other arm of said V-shaped plate, a prong on the inside of said other arm opposite the point of the first prong, and a spring for maintaining said first prong in engagement 50 with the cuff.

- 20 10. A cuff-clasp, comprising a substantially V-shaped plate adapted to embrace the meeting-edges of the cuff and provided with 55

an aperture in one of its arms, a button pivoted to said arm and covering said aperture in the cuff-fastening position, a prong attached to said button and movable through 60 said aperture and a button-hole in the cuff, prongs on the inside of said other arm forming a notch opposite the point of the first prong, and a spring movable with said first prong through said aperture and button-hole for maintaining said first prong in said notch in engagement with the cuff.

11. A cuff-clasp, comprising a substantially V-shaped plate adapted to embrace the 45 meeting-edges of the cuff and provided with an aperture near the end of one of its arms, a button pivoted to the outside of said arm and covering said aperture in the cuff-fastening position, a prong attached to the 50 under side of said button and movable through said aperture and a button-hole in the cuff, prongs on the inside of said other arm forming a notch opposite the point of the first prong, and a leaf-spring attached at 55 one end to said button beside said first prong but normally diverging from such prong along its free end for maintaining said first prong in said notch in engagement with the 60 cuff.

In testimony whereof, I affix my signature.

EVERETT B. STACKPOLE.
